UNITED STATES PATENT OFFICE.

LOUIS C. BELZ, OF PHILADELPHIA, PENNSYLVANIA.

PROCESS AND MEANS FOR MAKING DRAWN-WIRE ARTICLES.

1,239,451.

Specification of Letters Patent. Patented Sept. 11, 1917.

Application filed March 17, 1913. Serial No. 755,059.

To all whom it may concern:

Be it known that I, LOUIS C. BELZ, citizen of the United States, and resident of Philadelphia, county of Philadelphia, and State of Pennsylvania, have invented an Improvement in Processes and Means for Making Drawn-Wire Articles, of which the following is a specification.

The object of my invention is to provide a method and means for making a wire article having a portion of its length, intermediate of its ends, reduced in diameter, thereby providing a wire body with end portions of materially greater diameter and strength. Wire articles of this character may be made in various lengths and diameters, and the relative lengths of the portions of different diameters may be more or less varied; and may be utilized for the manufacture of tri-pronged hair pins such as set out in Letters Patent No. 1,026,142, granted to me on May 14, 1912, and for other purposes, wheel spokes, for example. These specially formed wires may be used for many purposes where tension is necessary, as they provide heavy ends suitable for receiving screw threads or of being upset or riveted, and they may also be used for tools, by proper subdivision and shaping.

My present application is especially directed to the method and means employed for reducing the diameter of a given portion or section of a wire by "wire-drawing" as distinguished from swaging or rolling. In carrying out my improvements, in the preferred manner, I provide means for producing a double "drawing down" action upon a given portion of the wire and a single "drawing down" action upon adjacent portions thereof, so that there are between the ends of largest diameter and the middle portion of smallest diameter, intermediate portions of short length of intermediate diameter thereby avoiding abrupt and great reductions in diameter.

In carrying out the operation, for producing the last above described form of my invention, I employ two sets of dies, one set operating to "draw down" the wire to the first diameter of reduction for a given length and the other set of dies acting to "draw down" the greater portion of the reduced section to a smaller or second diameter, said second set of dies then preferably so manipulated as to continue the "drawing down" of the full diameter to the

first diameter of reduction for a length, more or less, to suit the requirements to which the article is to be put.

My invention comprehends method and means which are fully described hereinafter and more specifically defined in the claims; and these improvements will be better understood by reference to the drawings, in which:

Figure 1 is a side elevation of a machine suitable for carrying out my improved method; Fig. 2 is an end elevation of the same with a part of one of the cams broken away; Fig. 3 is a sectional elevation on a larger scale showing the gripping means for pulling the wire through the dies; Fig. 4 is a sectional plan view on a similar scale showing one form of the "drawing" dies; Fig. 5 is a front elevation of the same showing the fin stripping means; Fig. 6 is a plan view of one of the completed wire articles (with portions broken away to shorten it); Fig. 7 is a diagram to illustrate the successive actions of the dies in their "drawing down" operations; Fig. 8 is an elevation of a modified shape of the drawn wire which may be made by my improved method, and Fig. 8^a is a view of one of the dies.

2 is the main frame of the machine, and 12 is the power shaft journaled therein and having secured to it the driving pulley 13 and the cam wheels 9 and 23 from which the various movements required by the machine may be derived. 5 is a die carrying frame, and is guided in a guideway 6 on the main frame, so as to be capable of vertical reciprocation. This frame 5 is provided with a horizontal guide slot 7^a in which a box 7^a is guided. 7 is a crank pin 90 journaled in the box 7^a and rotated by a pinion 8, said pinion being intermittently rotated by the teeth 10 and 11 of the cam wheel 9. The pinion 8 has upon its periphery, at diametrically opposite sides, two curved parts 8^a, which work in contact with the smooth perimeter of the cam wheel 9 to intermittently hold the pinion against rotation after each half revolution induced by the teeth 10 and 11. This pinion is provided with a shaft 8^c, journaled in a bearing 2^a, and is the direct means of rotating the crank 7, to raise and lower the frame 5. The upper part of the frame 5 has provision for two wire drawing dies 3 and 4, through which the wire is drawn by the traveling clamp 15. This clamp projects

downward from a slide 12^a guided in a horizontal extension 13^a of the frame 5. The upper surface of the slide 12^a is provided with a rack 14, which engages the pinion 16 and by which it is reciprocated. The pinion 16 is secured to one end of the shaft 17 which has a pinion 18 on its other end. 19 is a segmental rack, pivoted at 20 to the main frame and at the top engages the pinion 18 to rotate it first in one direction and then in the other. This segmental rack 19 is hinged to one end of a bar 21, carrying at its other end a roller 21^a, which is operated by a cam groove 22 in the cam wheel 23. This cam groove is so shaped as to impart to the slide 12 and its clamp 15 a reciprocating movement with such dwells as are necessary to suit the requirements, but the shape of this cam groove may be varied and would be, where various lengths of drawn wire are required. It will be understood, however, that when the frame 5 is lowered by the crank 7, the rack 14 is out of engagement with the pinion 16; and at such time the pinion should remain at rest.

The wire clamp 15 may be of any suitable construction, that shown being well adapted to its purpose. As shown, in Figs. 1 and 3, the clamp has a conical socket 26, in which 30 fits a conical bushing 26^a having within it the two jaws 24 of the clamp. These jaws are forced toward each other by the balls 25 carried in slots in the bushing and rolling against the wall of the conical socket 26. 35 A spring 27 maintains the bushing and jaws in a normal clamping position. A lever 28, pivoted to the clamp frame 15, acts to move the bushing backward to loosen the clamping jaws and is operated by the cam 29^a on 40 the end of the horizontal frame 13^a (Fig. 1), the arrangement being such, that when the clamp 15 is moved to the right, in its act of drawing the wire through the dies 3 and 4, the lever 28 strikes the cam 29 and 45 releases the wire. This clamp is so made, that when the wire is entered it cannot be pulled out until the lever 28 is moved; it therefore automatically takes hold of the wire adjacent to the dies and liberates it 50 when drawn through the dies to the predetermined length.

When the wire is drawn down in the manner to be described, the frame 5 is lowered to bring the wire into the shears 41 to sever it adjacent to the dies. The shears are composed of pivoted cutters arranged to be moved together by cams 42 on the part 13 of the frame 5, the said shears being supported upon the stationary main frame 2. 60 In this manner the wire may be cut off in given lengths. Any suitable shears or cutting off devices may be used.

Considering now the drawing dies, they are the same in all material respects except 65 that the dies 3 have a larger opening than

the dies 4. Referring to Fig. 4, 3^a is a box which is fitted into the die carrying frame 5 and has a longitudinal aperture in which the die plates 31 and 32 fit. These die plates are held in alinement by the box 3^a and by the pin 29 secured to the plate 32 and adjustably fitting plate 31 so as to prevent relative longitudinal movement between the plates while permitting slight lateral movement. These plates 31 and 32 are provided with the drawing dies proper 30 which, when close together, form a hole of the diameter corresponding to which the wire is to be drawn. Set in the box 3^a and resting against the die plate 32 is a hard steel block 33 to receive the direct thrust of the adjusting screw 34 and transmit its pressure to the dies.

The dies 3 are shown in Fig. 4, but dies 4 are the same, only the dies proper 30 provide a smaller hole as these dies reduce the wire to its smallest diameter, and no further description of the dies 4 will be required.

The screws 34 and 34^a for respectively operating the dies 3 and 4 are made with right and left hand threads respectively as indicated in Fig. 1. These screws work in the die carrying frame 5 and each has a crank arm 35 connected by a link 35^b so that when one screw is screwed in, the other is screwed out or vice versa, whereby the dies 3 and 4 are alternately brought into and out of operation to draw down the wire. The screw 34 is provided with a long arm 35 by which it may be oscillated and this arm is connected by link 36 with the lever 37 having a roller 38 which travels in the cam groove 9^a. This cam groove is so formed that different degrees of oscillation of the lever 37 may be secured; thus, the cam part 9^e causes the lever 37 to be at its lowest position and with the die 3 under pressure to draw down the wire and the die 4 open, the cam part 9^d causes the lever 37 to be raised to its highest position and with the die 3 open and die 4 closed under pressure for drawing down the wire, the part 9^e holds the lever in its raised position for a given period of the whole cycle of the operation of the machine, cam part 9^f lowers the lever 37 to an intermediate position with both dies 3 and 4 out of action and this is maintained for a given period of the operation by the part 9^g, and cam part 9^h lowers the lever 37 to its lowermost position to again put the die 3 into operative condition and die 4 out of operative condition. The opening 9ⁱ in the cam groove 9^a is to enable the roller 38 to pass down out of the groove, when the frame 5 is lowered as before explained to bring the wire down into the cutters 41.

The dies 3 and 4 may be provided with the stripping blades 39 pressed together by springs 40 (Figs. 4 and 5), to strip from 130

the wire any fin parts which may be formed when the dies bite upon the wire at the beginning of the operations of drawing down the wire.

5 In Fig. 6 is shown the finished wire. The parts AA are of the full diameter of the wire and may be of any desired lengths for which the machine may be designed, and the connecting portions BCB are those portions 10 of the wire that have been drawn down or reduced in diameter. The parts BB are reduced by dies 3 and then by the dies 4. The steps in the process for drawing down the metal in these parts B, C, B, are diagrammatically illustrated in Fig. 7. Assuming 15 that the wire is being drawn in the direction of the arrows through the dies 3 and 4, it will be seen that in step (1) the part B has been drawn down by dies 3 for a given 20 length somewhat greater than the distance between the dies 3 and 4. When this is accomplished, dies 3 are opened and dies 4 are closed to reduce part B to the diameter C as indicated in step (2). In this case, 25 the elongation of part B by dies 4 takes place to a great extent and furthermore the reduction begins at a given distance from one part A and terminates at an equal distance from the other part A. When this 30 latter condition is reached, the dies 3 and 4 are both brought to an intermediate condition of adjustment, when neither of the dies is operating upon the wire and we have the step shown at step (3). After the wire 35 moves through the dies a given distance to the position shown at step (4), the dies 3 are caused to close upon the wire and dies 4 open, and then we have step (1) repeated. When step (4) has been reached, the wire 40 is cut off by the cutters 41 as before explained. The parts C are shown in Fig. 7 as broken to indicate that any desired length 45 may be had according to the design of the machine. This is also true of the parts A and B.

While the dies are ordinarily operated to form the parts BB of uniform diameter throughout their lengths, it will be understood that this is only because the clamp 15 50 is intermittently pulled along by the action of the cam 22 said cam being provided with dwell portions.

Referring now to the general operation of the machine here described as an example of a suitable apparatus for carrying out the method of forming the special drawn wire articles to which this invention is directed, the same will be understood from the following explanation: Assuming the 55 parts of the apparatus to be in the positions indicated in Fig. 1, and keeping in mind that the cam wheel 9 rotates in the direction of the arrow, the wire A (indicated by dotted lines) will extend into the draw clamp 15, and moreover, as the roller 38 is

at its lowermost position in the cam way, the die 3 will be closed up tight upon the wire and the die 4 open, said dies being in the position indicated at (1) Fig. 7. The rotation of the shaft 12 with the cam wheels 9 and 23 will maintain these dies in the condition just mentioned, and will, during this period, oscillate the pivoted rack 19 a given distance which will correspond to the length of the part B of the diagram (1) Fig. 7. When this is accomplished, the cam portion 9^d comes into play and raises the roller 38 and unscrews the right-hand screw 34 and screws up the left-hand screw 34^a with the result that the dies 3 open up and the dies 4 close in tight to produce the reduction of the wire to the smaller diameter C, which, together with the new position of the dies, is indicated in diagram (2) Fig. 7. Immediately after the dies have assumed these new positions; the rack 19 is moved still farther by the cam groove 22 of cam wheel 23, and this causes the draw clamp 15 to be moved to the right a farther distance equal to the length of the smaller drawn diameter C of said diagram (2) Fig. 7. The relative distance of movement of the draw clamp is so proportioned in respect to the drawn parts of the wire, that there may remain at each end of the smaller drawn section C the larger drawn sections BB, and the relative lengths of these parts may be anything desired by properly proportioning the dies to the total diameter of the wire to be drawn and the distance through which the draw clamp is to be moved in any given operation of the dies. As soon as the wire has been drawn to the conditions indicated in the diagram (2) Fig. 7, the dies 4 open and the dies 3 partly close, so that neither of the dies is actually pressing upon the wire. This condition is brought about by the action of the cam portion 9^f of the cam wheel 9. When this condition of adjustment of the dies takes place, the dwell portion 9^g maintains the dies in this condition of adjustment while the cam 22 of the cam wheel 23 produces a further action of the rack 19 to cause the draw clamp 15 to pull the wire freely between the dies without action, which operation is indicated in the diagram (4) Fig. 7. When this is accomplished, the lever 28 of the draw clamp 15 will be brought into contact with the cam 29 on the end of the draw frame structure 18, and this will open the clamp to permit the wire to be drawn therefrom. While the parts are in this condition, the cam portion 9^h of the cam wheel 9 comes into play to lower the roller 38 with the result that the dies 3 are brought together and the dies 4 are opened wide, as indicated in diagram (1) Fig. 7, (but without the wire being drawn as in said diagram), this being the initial pinching operation upon the 130

wire to start the drawing operation to produce the reduced diameter B of said diagram (1) Fig. 7. Immediately upon completing the drawing operations above described, the further rotation of the cam wheel 9 will bring the open part of the cam slot 9^b under the roller 38, so that the roller 38 may descend therethrough and below the cam wheel 9 when the gear teeth 10 thereof impart a semi-rotation to the pinion 8 for the purpose of lowering the die carrying or draw bar frame 5. When this frame descends, the wire is passed between the cutters or shears 41 and the cams 42 thereof 45 operate to cause said shears to cut off the wire. The action of the gear teeth 11 on the cam wheel 9 is next to act upon the pinion 8 to give it a second semi-revolution to again raise the die or draw frame 5 to the 20 position indicated in Fig. 1. The cam groove 22 of the cam wheel 23 then acts to reciprocate the rack 19 in the direction the reverse to that of the arrow in Fig. 1 to return the draw clamp 15 to a position to receive the end of the wire projecting from the dies, namely, to the position indicated in Fig. 1. This being accomplished, the several steps are repeated to draw a second wire article, and so on.

When the dies pinch the wire when clamped tight upon it at the initial operation of biting upon the wire, there is a tendency to produce a small fin, which, on account of the pinching action, is quite brittle and may 35 be easily broken off. To insure this breaking away of the fins to leave a clean article, I provide the fin scrapers 39 at the rear end of each of the dies (Figs. 4 and 5), by which the fins are scraped off the wire, this 40 action, however, only taking place during the drawing operation.

I have described my invention in respect to the general process and the means employed for drawing wires with different 45 diameters in the direction of the length, and do not wish to be in any wise limited as to the relative lengths of the parts of different diameters, as these lengths may be anything desired, this being merely due to design of 50 the machine to give it more or less travel of the wire clamp 15 with a given operation of the dies. While I have also shown my improvements with the vertically movable die or draw frame and prefer to use such construction in connection with the adaptation 55 of my invention in the making of hair pins, I do not at all restrict myself to this vertical movement, as the drawing operation is completed without such vertical movement.

60 The cutting off of the wire may be performed in any suitable manner described, either by hand or by automatic devices. I have further shown the details of the cams and operative parts in the form which I 65 have designed for special application of my

invention in the production of drawn wire articles, more especially intended for the manufacture of hair pins, but I do not confine or restrict myself in any manner to the details here shown, as these may be modified in various ways without departing from the spirit of the invention.

Having now described my invention, what I claim as new and desire to secure by Letters Patent, is:

1. The hereindescribed method of wire-drawing wire strands, which consists in moving a wire in the direction of its length during said operation and wire-drawing a definite length of the wire to reduce its diameter, and then during the continued movement of the wire wire-drawing a part only of the total length of the portion of reduced diameter to produce a greatly reduced diameter connected with the wire portions of normal diameter by the reduced portions of intermediate diameter, the two wire-drawing operations taking place alternately and with one continuous movement of the wire.

2. The hereindescribed method of wire-drawing wire strands, which consists of moving a wire strand and during said movement subjecting the wire strand to two successive and superimposed wire-drawing operations, the first of which extends over a portion of the strand intermediate of its ends, and the other of which is done on that portion only of the length of the strand which was subjected to the first wire-drawing operation.

3. The hereindescribed method of wire-drawing wire strands, which consists of moving a wire strand and during said movement subjecting the wire strand to two successive and superimposed wire-drawing operations, the first of which extends over a portion of the moving strand intermediate of its ends, and the other of which extends for that portion only of the length of the strand which was subjected to the first wire-drawing operation and greatly reduces the cross section of the reduced strand, whereby the intermediate portion is made of relatively great length and small uniform cross sectional area and connected with the normal ends of the strand by relatively shorter lengths having cross sectional areas greater than the smaller cross sectional area and smaller than that of the normal strand.

4. In a machine for producing a double superimposed wire-drawing of a wire strand, the combination of two wire-drawing dies arranged in alinement so that the wire strand passes successively through said dies, a wire-drawing clamp or chuck to pull the wire through the dies, means for moving the clamp or chuck, and means for putting said dies into and out of operation alternately during the movement of the clamp or chuck,

- whereby one die operates upon a less mass of the wire strand than the other die.
5. In a machine for producing a double superimposed wire-drawing of a wire strand, the combination of two wire-drawing dies each consisting of two parts in adjustable relation said dies arranged in alinement so that the wire strand passes successively through said dies, a wire-drawing clamp or 10 chuck to pull the wire through the dies, means for moving the clamp or chuck, and means consisting of right-hand and left-hand adjusting screws for the respective dies and means for simultaneously operating 15 the screws for putting said dies into and out of operation alternately during the movement of the clamp or chuck, whereby one die operates upon a less mass of the wire strand than the other die.
- 20 6. In a wire-drawing machine, the combination of two sets of dies arranged in alinement and respectively providing drawing apertures of different sizes, means for drawing a wire strand simultaneously through 25 the two sets of dies, and means for alternately putting the two sets of dies into and out of operative adjustment and in which one set of the dies is in wire-drawing action a longer period of time than the other set 30 of dies, said dies reducing a portion only of the length of the strand.
7. In a wire-drawing machine, the combination of two sets of dies arranged in alinement and respectively providing drawing 35 apertures of different sizes, means for drawing a wire strand simultaneously through the two sets of dies, means for alternately putting the two sets of dies into and out of operative adjustment and in which one set 40 of the dies is in wire-drawing action a longer period of time than the other set of dies, said dies reducing a portion only of the length of the strand, and means for cutting off the wire-drawn strand at places in its 45 nominal portions.
8. In a wire-drawing machine, the combination of two sets of dies provided with drawing apertures of different sizes, means for drawing a wire strand through the two 50 sets of dies whereby they may successively act upon the same portions of the strand, means for simultaneously closing one set of the dies and opening the other set and vice versa, and connecting means for timing the

means for drawing the wire strand through 55 the dies and means for closing and opening the dies to cause the two sets of dies to respectively wire-draw different masses of the metal of the wire strand, whereby one set of dies reduces only a portion of the length of 60 the strand which was reduced by the other set of dies.

9. In a wire-drawing machine, the combination of two sets of dies provided with drawing apertures of different sizes, means 65 for drawing a wire strand through the two sets of dies whereby they may successively act upon the same portions of the strand, means for simultaneously closing one set of the dies and opening the other set and vice 70 versa, connecting means for timing the means for drawing the wire strand through the dies and means for closing and opening the dies to cause the two sets of dies to respectively wire-draw different masses of the 75 metal of the wire strand, whereby one set of dies reduces only a portion of the length of the strand which was reduced by the other set of dies, and means for cutting off the strand into lengths at normal or unre- 80 duced portions.

10. In a wire-drawing machine, the combination of two sets of dies provided with drawing apertures of different sizes, means for drawing a wire strand through the two 85 sets of dies whereby they may successively act upon the same portions of the strand, means for simultaneously closing one set of the dies and opening the other set and vice versa, connecting means for timing the 90 means for drawing the wire strand through the dies and means for closing and opening the dies to cause the two sets of dies to respectively wire-draw different masses of the metal of the wire strand, whereby one set 95 of dies reduces only a portion of the length of the strand which was reduced by the other set of dies, cutters for severing the wire strand into lengths, and means for moving the dies and means for drawing the wire 100 through the dies to and from the cutters for severing the wire strand.

In testimony of which invention, I hereunto set my hand.

LOUIS C. BELZ.
